(57) CLAIM

We claim the ornamental design for a hitch pin, as shown and described.

DESCRIPTION

FIG. 1 is a perspective view of a hitch pin showing our new design;

FIG. 2 is a right-side elevation view thereof;

FIG. 3 is a left-side elevation view thereof;

FIG. 4 is a front elevation view in use thereof;

FIG. 5 is a back elevation in use thereof;

FIG. 6 is a top plan view thereof;

FIG. 7 is a bottom plan view thereof; and,

FIG. 8 is a second perspective view thereof, showing the hitch pin.

The broken lines depicting a lock are for the purpose of illustrating the unclaimed portions of the article and form no part of the claimed design.
